JOSEPH B. KISLINGER, OF NEW YORK, N. Y., ASSIGNOR TO MARIE B. KISLINGER, OF NEW YORK, N. Y.

NOVELTY WATCH

Application filed June 23, 1924. Serial No. 721,721.

This invention relates to pendants, and more particularly to pendants adapted to constitute time pieces.

An object of this invention is to provide a device of the character described which will be ornamental and useful and which may be carried about the neck in a position convenient of access, but which will be so constructed that the mechanism will be protected 10 from damage due to dust and shock.

A further object is to provide a device of the character described in which the casing may be constructed of glass or other similar material, but so designed that full protection 15 will be given to the watch movement.

Other objects of the invention will in part be obvious and will in part appear herein-after.

The invention accordingly comprises the 20 features of construction, combinations of elements, and arrangement of parts, which will be exemplified in the constructions herein-after set forth and the scope of the application of which will be indicated in the claims.

For a fuller understanding of the nature 25 and objects of the invention, reference should be had to the following detailed description taken in connection with the accompanying drawing, in which:

Figs. 1, 2 and 3 are respectively a front, 30 side and rear elevation of a watch embodying this invention;

Fig. 4 is a section on the line 4—4 of Fig. 1 slightly enlarged;

Fig. 5 is a fragmental section on the line 35 5—5 of Fig. 2;

Fig. 6 is a section along the line 6—6 of Fig. 5;

Fig. 7 is a different embodiment of the invention.

The numeral 1 designates a member which may be flat pear shaped and is of material to form a transparent front face 2, which may serve as a lens of the watch. In the embodiment of Fig. 1, the periphery of the member 1 is provided with an edge 3 which may be engaged by a band 4 which completely encircles it. This band 4 is attached at its upper end to a sleeve 5. Attached to the sleeve 5 is a suitable bow 6 for the reception of a

ribbon or chain for supporting the watch around the neck.

In the rear of the member 1 there is provided a recess 7 capable of receiving a watch movement 8. A convenient and efficient manner of retaining the movement within the recess is illustrated, in which there is cemented or otherwise mounted within the recess, a sleeve 9, carrying means for retaining the movement within the recess, as for example, the sleeve 9 may carry upon its inner face screw threads 10 adapted to co-operate with mating threads upon the exterior of the watch movement. The recess 7 is formed as shown at 11 to provide ample space for the face and hands and the watch movement itself is completely enclosed in a dustproof case 12 within the recess. The recess 7 is so formed at its inner end as to provide a shoulder 13 against which the front edge of the movement may rest when in assembled position.

The recess 7 is itself closed by a cap 14, hinged as at 15 to one side of the sleeve 9.

The winding mechanism may be carried through an opening 16 through the bottom of the member 1 and in this opening may be cemented or otherwise mounted a sleeve 17 adapted to serve as a journal for a stem 18 provided at its outer end with a knurled knob 19 which may have an ornamental gem as 80 at 20. The stem 18 may be inserted through the passage or opening 16 and secured to the watch movement in any well known manner, for instance by ordinary screw threads.

By reason of the fact that the movement is 85 completely enclosed in a dust-proof case, inside of a case comprising the member 1, the sleeve 9 and the cap 14, it will be seen that it is fully protected against both dust and shock.

The construction of Figs. 5 and 6 affords a 90 very desirable and convenient method of attaching the band 4 to the sleeve 5. This band, which may conveniently be of general V shape in cross section to encircle the edge of the member 1, has its free ends projecting upwardly as shown at 21—22, and these may readily be formed into semi-circular shape as shown. To the interior of one of these extensions as 22, there may be sweated as at 23, a tube 24, having a threaded interior as shown 100

at 25. The two extended ends 21—22 when brought together around the tube 24 form a cylindrical surface which may be turned down to form a journal surface 26 for the reception of the sleeve 5 in which are pivoted as at 28 the ends of the bow 6. A suitable screw 29 screws within the interior of the tube 24 in order to retain the sleeve 5 in place, but the under surface of the head of this screw is preferably arranged to provide as little contact surface with the sleeve 5 as possible in order to reduce the tendency which the rotation of the sleeve 5 might have toward the loosening of the screw 29.

15 This form of construction permits the ready assembling and disassembling of the watch. By removing screw 29, the sleeve 5 may be immediately slipped from the journaled surface 26 to free the extension 21 from 20 the inner tube 24, whereupon if the stem 18 has been removed, the band 4 may be readily removed. This feature of construction is claimed in my Patent 1,600,889.

As illustrated in Fig. 1, the member 1 is 25 preferably ornamented, as for example, it may be molded or cut with refracting facets.

In the modification illustrated in Fig. 7, the band 4 may be omitted and the pendant supported by means of a canopy or hood 30, which 30 may be attached to the member 1 by rivets 31. This member 30 carries at its upper end a staff 32 on which may be supported a sleeve 33 carrying a bow 34, and this sleeve 33 may be retained upon the staff 32 by means of a 35 screw 35.

In this embodiment of the invention, the canopy 30 is preferably made of ornamental filigree. In this modification the sleeve 17 for the stem 18 may be utilized as before.

40 Since certain changes may be made in the above article and different embodiments of the invention could be made without departing from the scope thereof, it is intended that all matter contained in the above description 45 or shown in the accompanying drawing shall be interpreted as illustrative and not in a limiting sense.

It is also to be understood that the following claims are intended to cover all of the 50 generic and specific features of the invention herein described, and all statements of the scope of the invention, which, as a matter of language, might be said to fall therebetween.

The method of securing the band and bow 55 in place as shown in Figs. 5 and 6 and described herein, is broadly claimed with improvements in my application #73,343, filed Dec. 5th, 1925.

Having described my invention, what I 60 claim as new and desire to secure by Letters Patent, is:

1. A pendant construction comprising a watch movement having a face plate, a metallic case enclosing the edge and back of said 65 movement, a non-metallic body materially

larger than and enclosing said metallic case, a metallic band embracing the edge of said body, a supporting pendant attached to said band and a winding stem extending outwardly through said band and preventing relative 70 rotation of the movement in the body.

2. A watch construction comprising a watch movement having a face plate, a metallic inner case enclosing all of said movement except the face plate, a non-metallic body embracing the edge of said case and having a transparent portion extending over the face plate through which said face plate is visible, the upper end of said body being tapered and the lower end being substantially semicircular in 80 outline, a split metallic band embracing the outer edges of said body, means for clamping the ends of said band together to draw said band tightly on to said body, said inner case and said outer band serving to reinforce said body inside and outside respectively. 85

3. A watch construction comprising an ornamental body of substantial thickness and strength having a receiving recess, a lens at one face of the body, and a bevelled outer edge, a watch case in said recess, a watch movement enclosed in said case with its face visible through said lens, a split metallic band of V-shaped cross section fitting the bevelled edge of said body, a winding stem extending 95 from said watch movement outwardly through said case and through one edge of said body and said band and pendant means independent of said stem for detachably securing the ends of said band together to hold 100 said body, said body extending outwardly beyond the edge of said watch case and providing extended ornamental surfaces on both sides of said body around said watch case.

4. As an article of manufacture, a transparent flattened pear-shaped watch supporting body having a recess for receiving and supporting a watch case in its larger end, a convex magnifying lens portion opposite said recess, and ornamental refracting facets on 110 both sides around said recess, said lens portion projecting outwardly beyond the contour of the faceted portion, said body having a passage in one edge for the winding and setting stem of a watch extending outwardly 115 from said recess.

5. A watch construction comprising a rigid transparent body having a lens and a recess behind the lens, a watch case secured in said recess reinforcing and reinforced by said body 120 a watch movement in said case with its hands visible through said lens, a winding stem extending through one edge of said body and to said watch movement, a closure for the back of said recess and a bow at the upper end for 125 supporting said body.

6. A pendant watch comprising an elongated body pointed at the upper end, the outline being convex at its sides and the edges being beveled, a band gripping the beveled 130

edges and terminating in oppositely disposed members forming a bearing at the upper end, a sleeve on said bearing, a bow secured to said sleeve, a watch movement mounted in the lower end of said body and visible from the front and a winding stem projecting from said movement through the lower edge of said body and band and preventing said movement from rotating in said body.

5 7. A watch construction comprising a body, a watch movement mounted therein, a band embracing the edge of said body and terminating in two ends side by side, a sleeve surrounding said ends and holding them together, a screw having a threaded engagement between said ends and having a head for holding said sleeve in place, and a winding stem extending from said movement outwardly through said body and said band.

10 8. A watch comprising a metallic casing, a movement within the casing, a face external to the casing, a body entirely enclosing and reinforcing said casing and consisting of a non-metallic member larger than said casing and having a lens at the front of said movement, and a back member for said body, means for clamping at least one of said members including a circumferential metal band embracing and reinforcing said non-metallic member, means for winding said movement extending through said band to the exterior and a supporting ring attached to said band.

25 9. A watch comprising a watch case and movement having a face and hands, a body embracing said movement and consisting of a non-metallic member in front of said movement reinforcing the movement and having a transparent portion opposite said movement, and a second member back of said movement, a metal band having substantially straight end portions making an acute angle with each other and a central portion tangent to both of said portions, said body member having a periphery conforming to the shape of the said band, and means for clamping said end portions together to draw said band around said body member whereby strain is imposed upon said band in the direction of its length to hold said band and body members tightly together and reinforce said body member.

35 10. A watch case comprising, in combination, two body members adapted to be placed in juxtaposition, and having a cavity between the juxtaposed faces, a metallic watch case and a movement within said cavity reinforcing said body member, one of said body members having a channel adapted to afford communication between said chamber and the exterior, and a stem within said channel connected to said movement, and detachable means for holding said members comprising a metallic band and means for clamping said band about said members.

45 11. A watch case comprising, in combina-

tion, two body members, at least one of said members being of non-metallic substance and having a recess and having a channel affording communication between said recess and the periphery, a metal case within said recess, and a watch movement enclosed therein having a winding stem extending through said case and said channel, one of said members having a projecting periphery, a metallic band surrounding said periphery adapted to engage said projection to reinforce said member, and means for clamping said band about said member.

50 12. A watch construction comprising a metallic watch case having a face plate, a rim and a back plate, a nonmetallic body having a recess for said watch case, said case fitting and supporting the walls of said recess at the back and around the edge of the face plate, a metallic band embracing and reinforcing the body, and a winding stem extending from the watch case outwardly through said body.

55 13. A watch case body formed of glass having a bearing rim and a recess adapted to receive a metallic watch case and having a shoulder for supporting the front edge of the metallic case with a side wall to fit and reinforce the periphery of the metallic case and having a magnifying lens portion opposite the recess, the rim of the body having 95 a bevelled edge for providing a seat for a clamping and reinforcing band.

In testimony whereof I affix my signature.
JOSEPH B. KISLINGER.
